UNITED STATES PATENT OFFICE.

NELSON M. BRINKERHOFF, OF MELMORE, OHIO.

THILL-COUPING.

SPECIFICATION forming part of Letters Patent No. 269,630, dated December 26, 1882.

Application filed September 30, 1882. (No model.)

To all whom it may concern:

Be it known that I, NELSON M. BRINKERHOFF, a citizen of the United States, and a resident of Melmore, in the county of Seneca and State of Ohio, have invented a new and valuable Improvement in Thill-Couplings; and I do hereby declare that the following is a full, clear, and exact description of the construction and operation of the same, reference being had to the annexed drawings, making a part of this specification, and to the letters and figures of reference marked thereon.

Figure 1 of the drawings is a top or plan view of my coupling. Fig. 2 is a sectional view of the same, and Fig. 3 is a detail view.

This invention relates to a thill-coupling in which the eye of the thill-strap is held between the ears of the shackle by means of a bolt passing through said eye and ears; and it consists in the construction and novel arrangement of parts, as will be hereinafter more fully described, and pointed out in the claims appended.

In the drawings, A indicates the thill-strap, provided with an eye, a, which is held between the perforated ears b of the shackle B by means of a bolt which passes through said eye and ears. The bolt C is provided with a circular and rounded head, c, and with a pointed end, c', which latter allows the bolt to be readily inserted into and passed through the thill-strap eye and perforated ears of the shackle, and also through an elastic washer, D, which is interposed between the head of the bolt and one of the ears of the shackle. The bolt is further provided with a rectangular slot, E, near its pointed end, which slot extends through a portion of the projecting end of the bolt, and also through that portion of the bolt which has its bearing in the shackle-ear at this side of the shackle.

F indicates the key which is inserted in the slot to prevent the bolt from slipping out of its bearings. This key is provided upon its inner edge with a lateral projection, f, formed so as to provide at its lower end an offset or shoulder, f', the upper portion of the projection being inclined back to the body of the

key, as at f''. This key cannot be passed vertically through the slot, owing to said projection, and hence to insert the key it must be first somewhat inclined, and the washer compressed by tapping or pressing upon the bolt-head, in order to give a greater length of slot beyond the ear of the shackle. The projection will then enter the slot and its offset extend into that portion of the slot which is within the ear. The shoulder f' will then rest upon the wall of the perforation in the shackle-ear, and hence be prevented from dropping through the slot. The elastic washer, while preventing the bolt from turning, will also keep the key well up against the shackle-ear, and thereby maintain the projection on the key in place at the inner end of the slot and within the shackle-ear. The key can readily be withdrawn by a reversal of the operation by which it was inserted in the slot.

Having thus described my invention, what I claim is—

1. The combination, with the bolt having a slot at one end, of the elastic washer fitted upon the bolt between its head and one of the shackle-ears, and the key which fits in the slot of the bolt, provided with a projection which, when the bolt is in place, is received in that portion of the slot which lies in the perforation through the remaining shackle-ear, substantially as described.

2. The combination, with the shackle B, having two perforated ears, of the slotted bolt C, which passes through said ears, the key F, provided with a projection having a shoulder, f', and an incline, f'', and the elastic washer D, fitted upon the bolt between its head and one of the shackle-ears, said members being arranged substantially as and for the purpose specified.

In testimony that I claim the above I have hereunto subscribed my name in the presence of two witnesses.

NELSON MARQUIS BRINKERHOFF.
